BASE FOR A VISE, A FOOD GRINDER, AND THE LIKE

Herbert Friedman, New York, N.Y., assignor to General
Slicing Machine Co., Inc., Walden, N.Y., a corporation
of New York

Filed Oct. 19, 1961, Ser. No. 67,151

Term of patent 14 years

(Cl. D54—13)

FIG. 1 is a perspective view of a base for a vise, a food grinder, and the like, with the broken line showing of a vise included for illustrative purposes only.

FIG. 2 is a perspective view of the base embodying my new design.

FIG. 3 is a front elevational view of FIG. 2.

FIG. 4 is a side elevational view of FIG. 2.

FIG. 5 is a top plan view of FIG. 2.

I claim:

The ornamental design for a base for a vise, a food grinder, and the like, substantially as shown and described.
